UNITED STATES PATENT OFFICE.

JULIUS DEHNST, OF HALENSEE, NEAR BERLIN, GERMANY.

PROCESS OF TREATING MINERAL OILS.

1,112,602.

Specification of Letters Patent.

Patented Oct. 6, 1914.

Application filed April 17, 1906. Serial No. 312,070.

To all whom it may concern:

Be it known that I, JULIUS DEHNST, doctor of philosophy, chemist, a subject of the King of Prussia, German Emperor, residing at 15 Joachim-Friedrichstrasse, Halensee, near Berlin, Kingdom of Prussia, German Empire, have invented new and useful Improvements in Processes of Treating Mineral Oils, of which the following is a specification.

This invention relates to the processes of treating mineral oils, in order to ameliorate the burning properties of certain oils.

Certain sorts of crude petroleum, for instance the so-called Texas or Ohio oil, have a very unpleasant smell, which is found also in the manufactured products from such crude petroleum. For this reason, the said oils, which are specially characterized by the presence of sulfur or sulfur compounds, are very unsuitable for the manufacture of burning oils. The special disadvantage of their unpleasant odor makes it almost impossible to obtain from these crude oils a good burning oil. Several attempts have hitherto been made to remove from the said oils the sulfur therein contained. The chief processes proposed for this purpose consist in treating the mineral oils with metal compounds capable of forming with sulfur sulfur compounds of the metals.

I have found that the unpleasant smell in the distillates from crude petroleum may be removed or diminished by mixing the mineral oil with sulfur and then, first, separating by distillation from the oil the constituents boiling at and below 150 degrees centigrade, whereupon, secondly, the oil is heated with the sulfur to temperatures above 150 degrees centigrade; but under conditions which will prevent the escape of the remaining constituents of the oil. The result mentioned is very unexpected, because the unpleasant properties mentioned have been hitherto attributed to the presence of sulfur in the oil.

Figure 1 of the drawings illustrates, in vertical section, an apparatus suitable for carrying out the first step of the present process. Fig. 2 illustrates, in vertical section, an apparatus suitable for carrying out the second step of the present process.

My process is carried out in the following manner: 1000 kilograms of crude petroleum are mixed with 30 kilograms of sulfur. This mixture is placed in the flask *a* of the

apparatus, shown in vertical section in Fig. 1 of the drawings. The mixture of crude petroleum and sulfur is indicated by *b* in Fig. 1. The flask *a* is connected with an inclined cooler *c*, with which is connected a vessel *d* for collecting the distillate. The mixture of crude petroleum and sulfur *b* is heated to the temperature of 150 degrees centigrade by means of the lamp *e*. The oils distilling off until the said temperature is reached are condensed by means of the inclined cooler *c* and collected in the vessel *d*. After the oils having a boiling point of 150° C. and below, have been distilled off, flask *a* and the inclined cooler *c* are disconnected, and flask *a* is connected with the reflux cooler *f* having a container *c'* for the cooling fluid, as water as shown in vertical section in Fig. 2. The mixture of crude petroleum and sulfur remaining after the evaporation of the oil components of the boiling points below 150 degrees centigrade is heated from 150 degrees centigrade until about 170 degrees centigrade until the evolution of sulfureted hydrogen has ceased, the heating being carried out under conditions which will prevent the distillates escaping. The reflux cooler must be kept at such temperature that the distillates are condensed and return to the flask. At a temperature a little above 150 degrees centigrade the action of the sulfur on the crude petroleum begins with evolution of sulfureted hydrogen. Before the said temperature of 150° C. has been reached, no evolution of sulfureted hydrogen takes place. The low boiling portions called by the terms "benzin," "gasolene," etc., have not the disagreeable odor of the oils mentioned, even if they are obtained from oils of bad odor. The objectionable odor is only found in the high boiling portions of the oils. The temperature of heating may be increased, but care must be taken that through the action of the reflux cooler no constituents of the oil distil off. The preliminary removal of the oils boiling below 150° C. is essential. The action of the sulfur begins only at temperatures above 150° C.

The oily vapors are condensed by the cooler and return to the heated oil, whereas the sulfureted hydrogen is conducted away from the apparatus by means of a pipe *f*. After the said evolution is finished the reaction is completed. The remaining oil is finally fractioned so that the distillates of

such boiling points as the workman desires to secure will be obtained. The sulfur as far as it is not evolved as sulfureted hydrogen remains in the residue after the distillation. The added sulfur ceases to act as soon as all the sulfur present in the oil has been removed as sulfureted hydrogen. The oil may be decanted from an excess of unchanged sulfur. The distillates obtained by this fractionated distillation may be treated in the usual manner, for instance, by repeated distillation or by successive treatments with caustic soda lye and sulfuric acid, combined, if desired, with distillation. It is necessary to separate the oils boiling below 150° C., because only after the said oils have been separated can action of the sulfur on the oil be obtained. The present process may be applied to all crude oils which contains sulfur, especially the so-called Texas or Ohio oil. The process may, however, also be used for treating Russian, Galizian or German crude oils which contain constituents of disagreeable odor. The amount of sulfur and the temperature of distillation required for the present process, may be varied according to the nature of the crude oil to be treated and the products desired. The skilled workman will ascertain these conditions by experiments.

The amount of sulfur to be added and the duration of the heating depend upon the amount of the components of disagreeable odor. If the quantity of such components present in the crude oil is large, a higher proportion of sulfur must be taken and the mixture must be heated for a longer time than if a smaller amount of such components were present.

What I claim as my invention and desire to secure by Letters Patent is:—

1. The process of treating mineral oils which consists in adding sulfur to mineral oils, distilling a portion off before sulfureted hydrogen is evolved and heating the remaining oil until the evolution of sulfureted hydrogen has ceased.

2. The process of treating mineral oils which consists in adding sulfur to mineral oils, distilling off the portions boiling at and below 150 degrees centigrade and heating the remaining oil at temperatures above 150 degrees centigrade until the evolution of sulfureted hydrogen has ceased.

In testimony whereof I have signed my name to this specification in the presence of two subscribing witnesses.

JULIUS DEHNST.
